(57) **CLAIM**

The ornamental design for an electric oven as shown and described.

DESCRIPTION

FIG. 1 is a perspective view of an electric oven showing our new design;

FIG. 2 is a front elevation view thereof;

FIG. 3 is a rear elevation view thereof;

FIG. 4 is a left-side elevation view thereof, a right-side elevation view being a mirror image thereof;

FIG. 5 is a top plan view thereof;

FIG. 6 is a bottom plan view thereof;

FIG. 7 is an enlarged view of portion 7 in FIG. 1; and,

FIG. 8 is a perspective view thereof, showing the door in an open position.

The broken lines shown in the drawings depict portions of the electric oven that form no part of the claimed design.

The long dash-short dash broken lines shown in FIGS. 1 and 7 represent cutoff boundaries for the enlarged detail portion view and form no part of the claimed design.
